CLAIM

The ornamental design for a non-pneumatic tire, as shown and described.

DESCRIPTION

FIG. 1 is a perspective view of a non-pneumatic tire of the present invention;

FIG. 2 is a front elevational view thereof, it being understood that the triangular and U-shaped elements arrayed along the sidewall are apertures extending the entire width of the non-pneumatic tire;

FIG. 3 is a rear elevation view thereof;

FIG. 4 is a right side elevation thereof;

FIG. 5 is a left side elevation view thereof;

FIG. 6 is a top view thereof; and,

FIG. 7 is a bottom view thereof.

In the drawings, the broken lines depict environmental subject matter only and form no part of the claimed design.
